UNITED STATES PATENT OFFICE.

ALBERT H. GEDDES, OF EMPIRE, PANAMA.

DIPPER-TRIP FOR STEAM-SHOVELS.

978,575.

Specification of Letters Patent. Patented Dec. 13, 1910.

Application filed June 21, 1910. Serial No. 568,075.

To all whom it may concern:

Be it known that I, ALBERT H. GEDDES, a citizen of the United States, and a resident of Empire, Canal Zone, Republic of Panama, have invented a new and Improved Dipper-Trip for Steam-Shovels, of which the following is a full, clear, and exact description.

This invention relates to dipper trips for steam shovels, dredges and the like, and has reference more particularly to the combination in a steam shovel with a dipper, a door therefor, and means for operating the dipper, of a latch for the door, a cylinder adapted to receive a fluid under pressure, a piston in the cylinder, and means for operatively connecting the piston and the latch, whereby the piston can be actuated to release the door.

The object of the invention is to provide a simple and efficient dipper trip for use in connection with steam shovels, dredges, and like machines for excavating and other purposes, by means of which the door of the dipper or bucket can be released mechanically, to empty the bucket, thereby obviating the necessity of pulling manually upon a rope or the like to release the door, and thus saving time and labor, which renders the operation of the steam shovel or dredge more rapid and economical, which can be operated by steam or other fluid under pressure, and which, after each operation, is returned to a normal position by means of a suitable spring.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a side elevation of a steam shovel having an embodiment of my invention applied thereto; Fig. 2 is an inverted plan view of a dipper or bucket, showing the latch for locking the door; Fig. 3 is an enlarged, fragmentary section of part of the cylinder, showing a constructive detail; Fig. 4 is an enlarged, side elevation of the end of the dipper stick or handle, showing in longitudinal section the cylinder; Fig. 5 is a longitudinal section on the line 5—5 of Fig. 4;

and Fig. 6 is a transverse section on the line 6—6 of Fig. 4.

Before proceeding to a more detailed explanation of my invention, it should be clearly understood that the same can be advantageously employed with steam shovels, dredges or other apparatus having dippers or buckets provided with releasable doors which are held closed by means of latches, and in which the latches can be released to permit the contents to escape from the bucket, in the operation of the apparatus.

Certain of the details of construction shown for example herewith, form no part of the invention, and can be varied in accordance with individual preference and special conditions, without departing from the underlying spirit of the invention.

Referring more particularly to the drawings, I have shown a steam shovel of conventional type, having a car 10 carried upon wheeled trucks 11, and adapted to run upon tracks. The car carries a boiler 12, for producing steam to operate the shovel, and is provided with a suitable engine for this purpose. At one end of the car is located the boom 13, mounted to swing, and carrying the dipper stick or handle 14, in the usual manner. An upright 15, is located at the end of the car, and is connected with the end of the boom, by means of tie members 16. The dipper stick or handle is fashioned from two channels 17, arranged back to back, and spaced, being secured together in any suitable manner. The dipper stick, controlled by the bull wheel 18, is arranged to move in the direction of its length. At the forward end it has a dipper stick casting 19 having upwardly disposed extensions 20, provided with openings 21. The dipper or bucket 22 has extensions 23 pivotally connected with the extensions 20 by means of a hinge pin 24, which extends through the openings 21. Link members 25 are secured to the dipper and to the dipper stick. The bucket has at the open end the usual bail 26, to which is connected the pad-lock 27. A pulley or chain 28 is attached to the pad-lock and passes over sheaves 29 to the operating engine, (not shown), in the usual manner. It will be understood that the engine actuates the chains to effect the operation of the bucket, and also serves to move the dipper stick, and to swing the boom.

A cylinder 30, open at one end, and pro-

110

vided at the other with a head 31, having a stuffing-box 32, is provided with flanges 33 secured by means of bolts 34, to one of the channels 17. Within the cylinder is a piston 35 having a piston rod 36 which passes through the stuffing-box, and has at the end, an eye 37, to which is secured a chain 38. The chain passes through a guide eye 39, secured upon the channel, and passes around 10 a grooved pulley 40, journaled upon the channel and acting as a guide. The chain passes around the pulley, to the door 41 of the dipper. The door has hinge arms 42, by means of which it is pivotally associated 15 with the hinge pin 24, and is thereby mounted to swing to close the rear end of the bucket, in the normal position. Upon the door is arranged a latch, including a bolt bar 43, the end of which, when inserted in a keeper 44, on the bucket, serves to hold the door closed. The bolt bar is pivotally secured to a lever 45 connected by a link 46 with a lever 47. The levers 45 and 47 are pivotally mounted upon the door, and are 20 pivotally connected by the link. The chain 38 is secured at the end of the lever 47. By drawing upon the chain, the bolt bar is retracted, to release the latch, to permit the door to swing open gravitationally, permitting 25 the bucket to empty.

At the open end, the cylinder has a spider 48 against which presses a spring 49. The spring likewise engages the piston, and tends to move it toward the head 31 of the cylinder. The chain has a ball 50 constituting a stop, which is adapted to engage the guide eye 39 and thereby to limit the movement of the chain. The cylinder, near the head, has an internal, annular shoulder 51 which 30 forms an abutment for the piston, and limits the movement thereof, and prevents the piston from engaging the head directly, thus forming a certain clearance. The cylinder, at one side, near the head has an extension 45 52, provided with a passage 53 communicating interiorly with the cylinder and with a passage 54 terminating in an enlarged threaded part 55, adapted to receive the correspondingly threaded end 56 of a union 57 50 mounted at the end of a flexible tube 58. The latter is connected with a three-way valve 59, mounted at the end of a pipe 60 which leads to the boiler 12, or to any other suitable source of supply for fluid under 55 pressure. The three-way valve has an operating handle 61, and an outlet 62. The operator's seat 63, is located at one end of the boom, so that he can conveniently control the three-way valve. The tube 58 may 60 be of any suitable kind, and is preferably wired, to prevent rubber or other material being carried into the cylinder. The passage 54 of the extension 52 is open at the end remote from the union 56, and has a 65 valve casing 64 mounted over the open end.

The valve casing has a seat 65 adapted to be closed by a valve 66, provided with a stem 67, passing through a guide 68. A spring 69 mounted upon the valve stem and engaging a lug 70 thereof, presses upon the 70 guide 68 and tends to hold the valve normally open.

In its normal position, the piston 35 is held against the stop shoulder 51 of the cylinder, by the spring 49. This permits 75 the chain to be extended so that the bolt bar of the latch is in operative relation with the keeper 44, and holds the door closed. After the dipper has been filled with material, and when it is desired to empty the 80 dipper, the three-way valve 59, which is normally closed, is opened to permit steam or other fluid under pressure to enter the cylinder, and to move the piston toward the open end of the cylinder, against the tension of the spring 49. This pulls upon the chain 38, and operates the latch to withdraw the bolt bar. The door swings open, and the 85 contents of the bucket escape. The three-way valve is then operated to open the outlet 62 to the atmosphere, and the steam within the cylinder escapes therefrom, the spring returning the piston to its normal position. The door of the bucket can then be again closed, and latched. The stop 50 limits the 90 movement of the chain. The spring 69 of the valve 66 is so adjusted that as soon as the pressure within the cylinder is materially reduced, the valve will open and the cylinder can be freed from accumulated 100 water of condensation, the piston serving to force the water from the cylinder, as it is returned to its normal position by the spring 49.

Having thus described my invention, I 105 claim as new, and desire to secure by Letters Patent:

1. In a steam shovel, the combination, with a dipper, a door therefor, and means for operating said dipper, of a latch for said door, a cylinder adapted to receive a fluid under pressure, a piston within said cylinder, means for operatively connecting said piston and said latch, whereby the latter can be released by said piston, means for holding said piston in a normal position such that said latch is operative to lock said door, and a stop carried by said means for operatively connecting said piston and said latch and serving to limit the movement of said piston. 115 120

2. In a steam shovel, the combination with a dipper, a door therefor, and means for operating said dipper, of a latch for said door, a cylinder adapted to receive a fluid under pressure and having a piston therein, a flexible elongated member connecting said piston and said latch, a guide for said member, and a stop on said member and adapted to engage 125 said guide to limit the movement thereof.

3. In a steam shovel, the combination with 130

- a dipper stick, a dipper carried thereby, a door for said dipper, and means for operating said dipper, of a cylinder mounted upon said dipper stick and adapted to receive a fluid under pressure, a piston in said cylinder and having a piston rod, a flexible member connecting said rod and said latch, a grooved guide pulley mounted upon said stick and having said flexible member pass around the same, a guide-eye mounted upon said stick and having said member pass through it, and a stop secured to said flexible member and adapted to engage said guide-eye to limit the movement of said member.
- 10 4. In a steam shovel, the combination with a dipper, a dipper stick carrying said dipper, a door for said dipper, and means for manipulating said dipper, of a latch for said door, a cylinder adapted to receive a fluid under pressure, and mounted upon said dipper stick, said cylinder having at one end a head and being open at the other end, a spider at said open end, a piston within said cylinder and having a piston rod, said head having a stuffing-box, said piston rod passing through said stuffing-box, a spring within said cylinder and engaging said piston and said spider and tending to move said piston toward said head, a chain operatively connecting said piston rod and said latch, a grooved guide pulley mounted upon said
- 15 dipper stick and having said chain pass around it, a guide-eye mounted upon said dipper stick and having said chain pass through it, and a stop upon said stop chain 35 and adapted to engage said guide-eye.
5. In a steam shovel, the combination with a dipper, a door therefor, a latch for said door, and means for operating said dipper, of a cylinder adapted to receive fluid under 40 pressure and having an inlet, a piston in said cylinder, an operative connection between said piston and said latch, a spring tending to hold said piston in a normal position such that said latch is operative to 45 hold said door closed, said cylinder having therein a stop shoulder serving to space said piston from one end thereof, said cylinder having an inlet, a pipe for directing fluid to said inlet, a valve for controlling said 50 pipe, said cylinder having a draining opening, and a valve controlling said draining opening and adapted to open when the pressure in said cylinder falls to a predetermined point.
